CONTAINER WITH MIXING DEVICE

Almont H. Koepf, Orinda, Calif., assignor to Kaiser Aluminum & Chemical Corporation, Oakland, Calif., a corporation of Delaware

Filed Oct. 23, 1961, Ser. No. 146,948
11 Claims. (Cl. 126—362)

This invention relates to a system for storing and handling fluids at elevated temperatures. More particularly, it relates to a unique system for storing and handling water at elevated temperatures, as well as certain unique components of such a system, wherein a unique arrangement is employed for storing hot water in an aluminum storage unit and for mixing or blending the hot water drawn from the storage unit with cooler water prior to use of the drawn water.

Accordingly, it is a primary purpose of this invention to provide a unique system, as well as unique components usable therein, for storing and handling water at elevated temperatures wherein a unique arrangement is employed for storing hot water in an aluminum storage unit and for mixing or blending the hot water drawn from the storage unit with a cooler water prior to use of the drawn water.

Other purposes and advantages of the instant invention will be more readily understood from a review of the following detailed description, when taken in conjunction with the accompanying drawings, throughout which like reference characters indicate like parts and wherein:

FIG. 1 is an elevational sectional view of a fluid mixing or blending device for use in practicing the instant invention;

FIG. 2 is a horizontal sectional view of the mixing device shown in FIG. 1, taken along the line 2—2 thereof and with parts removed for the sake of clarity;

FIG. 3 is a vertical sectional view of a typical hot water storage tank that may be used in practicing the instant invention; and

FIG. 4 is a graph illustrating the performance characteristics of a water storage unit provided with the mixing device of FIGS. 1 and 2.

In providing fluid at elevated temperatures, such as in the case of domestic hot water units, there has been considerable interest in the use of aluminum as the structural material for the hot water storage tanks. One of the major problems encountered in the use of aluminum hot water storage tanks concerns corrosion. The corrosion rate of aluminum exposed to water at elevated temperatures normally increases as the temperature of the water is increased from ambient temperature up to approximately 150° F. Then as the temperature increases from between 150° to 200° F., the corrosion rate decreases markedly. This phenomenon is explained by the structure of the different oxide films that form on the metal surfaces at temperatures above 150° F. and below 150° F. At water temperatures below 150° F., the oxide film is relatively thick, porous, and permeable and in the form of a tri-hydrate aluminum oxide, namely $Al_2O_3 \cdot 3H_2O$. This tri-hydrate oxide film has only moderately good resistance to corrosion and cannot be relied on to provide the necessary corrosion-resistant film required to make the use of aluminum in the wall structures of hot water storage tanks practical. Moreover, water heaters in normal residential use normally require water to be dispensed at temperatures of approximately 140° F.

As noted above, it has been found, rather surprisingly, that as the temperature of the water in an aluminum-walled storage tank increases from approximately 150° F. to about 200° F., the corrosion rate of the aluminum decreases markedly. This is due to the

2

formation of an oxide film on the water-exposed aluminum surfaces, which is thin, adherent and relatively impermeable and it is known as boehmite. Boehmite is a mono-hydrate oxide in the so-called gamma crystalline modification and has the formula $Al_2O_3 \cdot H_2O$. It is extremely resistant to corrosive attack, although it is not particularly stable at low temperatures at which transformation to the aforesaid tri-hydrate oxide occurs in time. However, in the case of the normal thermostatically controlled residential and commercial water heaters used today, the time periods involved in the cooling and re-heating cycles are so negligible that once established the oxide film formed on an aluminum water heater wall will for all practical purposes remain in its corrosion-resistant boehmite form.

From the above, it will be readily appreciated that the optimum storage temperature for water in an aluminum-walled hot water tank is above 150° F. A gradient of oxide film quality exists between 150° F. and 200° F. and it has been found in the case of most water that is commercially or domestically available that a temperature of approximately 180° F., produces the optimum gradient of film for all practical purposes. This temperature, on the other hand, is usually above the dispensing temperature desired for residential water systems because it is so hot that there is danger of burning the skin of persons with whom it comes in contact.

The problem of supplying hot water at the optimum temperature of about 140° F. while using the advantageous characteristics of a boehmite oxide film has been overcome by use of the novel mixing valve device of the instant invention wherein water at ambient temperature, normally between approximately 35° F. and 70° F., and referred to hereinafter as cold water, is mixed with water as it is drawn from the storage tank at temperatures above 150° F. When this mixing or blending of hot and cold water takes place, the final or outlet temperature of the drawn water is between a desirable 120°—150° F. and for all practical purposes in the neighborhood of 140° F. By use of the novel mixing valve device of the instant invention, it is possible to provide dispensed water at the desired consumption temperature, while still taking full advantage of the boehmite film formation needed to prolong the life of the aluminum-walled water storage tank by maintaining water temperatures in the desirable range of 150° F. to 200° F. and preferably at 180° F. in the storage tank. It is to be further observed that in water heater storage tanks made of materials other than aluminum, an increase in temperature above 150° F. normally causes rapid deterioration to occur. Galvanized steel, for example, is subjected to a galvanic potential reversal at these elevated temperatures. The steel becomes anodic to the zinc and rapid oxidation and deterioration of the steel results. Glass-lined steel is subject to rapid deterioration of the glass coating by thermal cracking at these elevated temperatures and with water of certain compositions, the glass material actually dissolves.

With further reference to the drawings, and in particular FIGS. 1-3, the novel mixing valve device 11 which is advantageously used in the instant invention can be mounted on the top of storage tank, such as the aluminum-walled storage tank A shown in FIG. 3. Tank A is comprised of side wall a, bottom b and top c. The mixing valve device acts to maintain the temperature of the water drawn from the tank A through conduit B at substantially a constant temperature of approximately 140° F. regardless of the rate of flow by mixing or blending the water withdrawn from tank A with the cold water from cold water conduit C.

The mixing device 11 includes a mixing block 13 provided with a mixing or blending tube 15 disposed within

the across the chamber 17 of the block 13. Chamber 17 also acts as a connection or coupling between the several segments 17' and 17" of conduit C. Mixing tube 15 has an orifice 19 for introducing cold water from conduit C into the bore 15' of the mixing tube 15 as the water is drawn from the storage tank A in a manner to be more full described hereinafter.

As indicated in the drawings, block 13 is also advantageously provided with a valve chamber 21. Chamber 21 is in open communication with the interior or bore 15' of mixing tube 15 through the medium of outlet 23 and with the interior of tank A through the medium of inlet 24 provided with the ball check valve 25. The ball 27 of valve 25 is adapted to seat by gravity upon the seat 29. In the preferred embodiment of the invention, seat 29 is advantageously provided with one or more by-pass grooves 31.

It has been found, when water is drawn from tank A through inlet 24, valve chamber 21, outlet 23, tube 15 and outlet element 33 of conduit B at fairly high rates of flow and with the orifice 19, outlet 23 and inlet 24 being of appropriate sizes, that the ball 27 is suitably displaced from the seat or seating portion 29 by the flow of hot water entering the valve chamber 21 from the storage tank as the cold water enters pipe C, and that at the same time the outlet temperature of the drawn hot tank water, when mixed with cold water entering tube 15 through orifice 19 can be maintained in the desirable range of between 120° and 150° F. and preferably at 140° F.

It has been further found if the check valve 25 is not present and only an orifice of comparable size to the outlet 23 is used, that when the flow rate and pressure of water becomes low (for example less than about 0.1 pound per square inch), the passage or entrance of cold water through the orifice 19 is usually blocked and the mixed outlet temperature of the drawn water in outlet element 33 approaches the temperature of the tank which, at 180° F., would be entirely too hot for ordinary usage. It would appear that one of the reasons for this is because the lighter hot water attempts to rise and counter the efforts of the heavier cold water to fall and enter the mixing tube 15 through the relatively small orifice or inlet 19. Thus, a stratification occurs and the cold water is prevented from entering the mixing tube or chamber 15. This in turn means that the mixing device would become a hazard at low flow rates and the hot water discharged at these low flow rates could easily burn the skin of a person using the hot water.

If a check valve is incorporated in the mixing or blending device 11, these temperature characteristics are markedly improved. If a ball 27, such as that shown in FIG. 1, is used with an ungrooved seating portion, the temperature at the low flow rates is not hot enough to be dangerous and, in fact, tends to fall below the desirable 140° F. because the ball 27 will tend to shut off the flow of the hot water from the tank at the low rates. In view of the aforesaid problems, it has been found that it is preferable to use additional inlet means or by-pass grooves in the seat 29, such as the grooves 31 shown in FIGS. 1 and 2. These grooves 31 allow a suitable amount of hot water even at low flow rates to by-pass valve 25 without completely blocking the inflow of the cold water through the orifice 19.

In order to maintain the mixed or blended cold and hot water drawn through outlet element or pipe 33 at the normal desired temperature of 140° F. while at the same time maintaining hot water temperature in the tank at approximately 180° F. and with the cold water entering pipe C being at ambient temperature of normally between 35° F. and 70° F., it has been found that the ratio of the cross-sectional area of the orifice 19 to the cross-sectional area of the outlet 23 should be approximately 1:2.

Mixing tube 15 provided with the internal mixing chamber or bore 15' can be of a suitable plastic material,

such as a hydrolysis-resistant nylon or high temperature resistant polypropylene compound. Block 13 can be made of a suitable aluminum alloy while the ball 27 can be made completely of aluminum, or a suitable plastic material, or it can have a metal core coated with a suitable rubber or plastic material. Internally and externally threaded bushings or seals 37 and 39 can be used if desired to seal the pipes or conductors C and 33 to the block 13. One end of tube 15 abuts against seal 39 and the other end of tube 15 abuts against the shoulder 23' of block 13 adjacent outlet 23. The use of removable plug 35 at one end of the valve chamber 21 also makes it easy to repair or clean valve assembly 25. Bottom surface 35' of plug 35 is so positioned during assembly that at high flow rates ball 27 will not seat itself in opening or outlet 23 and thereby cut off supply of hot water to mixing tube 15.

In some instances, it may be desirable to use an oversized valve chamber 21, such that comparatively high velocities can be developed when the valve is opened fully. The ball 27 will then be violently agitated and collide with the walls of the valve chamber 21, thereby loosening and removing undesirable deposits which tend to form on the walls of the valve chamber 21.

The advantageous operating characteristics of the mixing device of the instant invention is illustrated in the graph of FIG. 4. At flow rates of the water drawn from outlet pipe 33 of between 0 to about $\frac{3}{4}$ of a gallon per minute the temperature gradient of the water ranges between 120° F. to roughly 150° F., as indicated by curve segment Z. At steady flow rates of about $\frac{3}{4}$ of a gallon a minute, the temperature gradient of the drawn water is again between 120° F. and 140° F., as indicated by curve segment Y. At flow rates above $\frac{3}{4}$ of a gallon per minute the temperature of the drawn water is maintained at a constant optimum 140° F. temperature, as indicated by curve segment X. Thus, for all practical purposes, it can be said that in the normal use of the mixing device where the drawn water will, in most instances, exceed the $\frac{3}{4}$ of a gallon per minute flow rate, a substantially constant 140° F. temperature will be effectively maintained.

A further advantageous feature of the instant invention resides in the fact that due to the rise in the water temperature in the storage tank from the normal 140° F. to approximately 180° F., the effective hot water availability of the heater system is increased by approximately 50%. This is accomplished as a result of blending two units of hot water with one unit of cold water in the mixing tube 15. Thus, the discharge of water at a temperature of approximately 140° F. is at least 50% greater in quantity than the 140° F. water produced by normal hot water heater of comparable size. In addition, the heat input from natural gas firing unit 45 to the storage tank A can be similarly increased by at least 50% because of the superior thermal properties of the aluminum alloys used in tank A in comparison with the prior art steel storage tanks. The size of the burner unit 45 may be increased and the combustion passages may be adjusted to insure adequate heat retention. As the heat input rate may be increased, the recovery rate may be increased also. So-called hot spots do not develop with the aluminum alloys used, and other thermal structural weakening of the material is not present.

As pointed out previously, at the high temperatures used, aluminum alloys have excellent corrosion resistance due to the boehmite film formation, and, as used in this application, the term "aluminum" includes high purity aluminum, commercial aluminum and aluminum-based alloys containing at least 50% aluminum by weight.

It is to be further noted that although the preferred embodiment of the invention contemplates that tank or receptacle A would be made completely of aluminum, there may be instances where it would have made of a composite stock material, such as aluminum bonded to

other materials, either metallic or non-metallic, and with the aluminum surface portions of the composite stock material always being exposed to the water in tank A.

An advantageous embodiment of the invention has been shown and described. It will be obvious to those skilled in the art that various changes and modifications may be made therein without departing from the spirit and scope thereof as set forth in the appended claims, wherein in what is claimed is:

1. Apparatus for use in providing fluid at a predetermined outlet temperature by mixing fluid of a first temperature below the desired predetermined outlet temperature with fluid of a second temperature above said predetermined outlet temperature, said apparatus comprising in combination a container for receiving and storing the fluid of said second temperature, a mixing device affixed to said container, said mixing device being provided with a first inlet means in communication with the interior of said container, a second inlet means for the fluid of said first temperature, and a first outlet means and a second outlet means, said mixing device further including a valve means disposed adjacent said first inlet means and a mixing tube interposed between and communicating with said valve means and said first and second outlet means, said mixing tube being provided with an orifice means in open communication with said second inlet means for receiving fluid of said first temperature and for introducing the fluid of said first temperature into said mixing tube where it is adapted to mix with the fluid of the second temperature drawn from said container prior to the time the fluid is finally discharged through said first outlet means, said second outlet means also being interposed between and communicating with said mixing tube and said valve means, the cross-sectional dimension of said second outlet means being at a predetermined ratio to the cross-sectional area of the orifice means of said mixing tube.

2. A device as set forth in claim 1 wherein the valve means comprises a valve member and a valve seat for said valve member with said valve member being normally seated by gravity on said seat, said seat being further provided with groove means operable to allow fluid at said second temperature to by-pass said valve means when said valve means is substantially closed.

3. Apparatus for use in providing fluid of a predetermined outlet temperature by mixing a fluid at a first temperature below said predetermined outlet temperature with a fluid at a second temperature which is above both the predetermined outlet temperature and said first temperature fluid, said apparatus comprising the combination of a storage container for the fluid at said second temperature, a mixing device affixed to said container, said mixing device being provided with a first inlet means for receiving the fluid at the second temperature from said storage container, a second inlet means for receiving the fluid at said first temperature and an outlet means, said mixing device further including a valve means for said first inlet means, a mixing tube disposed in said second inlet means and intermediate said valve means and said outlet means, said mixing tube also connecting said valve means with said outlet means, said mixing tube being provided with a normally open orifice for placing the interior of said tube in communication with said second inlet means so as to allow the fluid at said first temperature to be mixed with the fluid at said second temperature prior to the discharge of the fluid at said predetermined outlet temperature through said outlet means.

4. A device as set forth in claim 3 wherein said valve means comprises a valve member and a seat for said valve member with said valve member being normally seated by gravity on said seat, said seat being further provided with groove means for allowing the fluid at said second temperature to by-pass said valve means when the valve member is substantially fully seated on said seat.

5. A device as set forth in claim 3 wherein the valve means is provided with an outlet means connecting said valve means with said mixing tube, and wherein the ratio of the cross-sectional area of said last-mentioned outlet means to that of the orifice of said mixing tube is 2:1.

6. In a water storage and dispensing system the combination of a storage receptacle wherein the surfaces of the receptacle that are exposed to the water consist of a metal selected from the group consisting of aluminum and aluminum alloys, means for heating said receptacle in order to raise and maintain the water in the receptacle above a predetermined elevated temperature so as to promote the formation and maintenance of a highly corrosion-resistant oxide film on the said inner surfaces of the receptacle, said system further including receptacle outlet means for dispensing the water at the said predetermined elevated temperature from the receptacle, receptacle inlet means for supplying fresh water to said receptacle at a temperature below the said predetermined elevated temperature and in quantities substantially equal to the quantities dispensed from and through said receptacle outlet means, a dispensing conduit, a fluid-mixing means interposed between said receptacle outlet means and said dispensing conduit and connecting said outlet means with said dispensing conduit, said mixing means also being connected to and in open communication at all times with said receptacle inlet means, whereby said mixing means can effect a mixing and blending of the water withdrawn from the receptacle at said predetermined elevated temperature through the outlet means and prior to entrance of said water at said predetermined elevated temperature into the dispensing conduit with at least a portion of the lower temperature water that enters the receptacle through said inlet means.

7. A system as set forth in claim 6 wherein the corrosion-resistant oxide film comprises $Al_2O_3 \cdot H_2O$.

8. A system as set forth in claim 6 wherein said receptacle outlet means includes a valve and a valve bypass means operable to pass water from the receptacle through the receptacle outlet means and to said fluid-mixing means at low rates of flow of water from the receptacle.

9. In a water storage and dispensing system, the combination of a storage receptacle wherein the surfaces of the receptacle that are exposed to said water consist of a metal selected from the group consisting of aluminum and aluminum alloys, means for heating said receptacle and for raising and maintaining the water in the receptacle above 150° F. so as to promote the formation and maintenance of a highly corrosion-resistant oxide film comprising $Al_2O_3 \cdot H_2O$ on the said inner surfaces of the receptacle, said system further including receptacle outlet means for dispensing the water from the receptacle, a dispensing conduit, a receptacle inlet means for supplying fresh water to said receptacle at a temperature substantially below 150° F. and in quantities substantially equal to the quantities dispensed from and through said receptacle outlet means, a fluid-mixing means interposed between said receptacle outlet means and said dispensing conduit and interconnecting said receptacle outlet means with said dispensing conduit, said mixing means comprising tube means provided with an orifice in open communication at all times with said receptacle inlet means and with the interior of said tube means whereby said mixing means can effect a mixing and a blending of the water above the 150° F. temperature withdrawn from the receptacle and prior to entrance of the said water above the 150° F. temperature into the dispensing conduit with at least a portion of the lower temperature water that enters the receptacle through said receptacle inlet means.

10. In a water storage and dispensing system as set forth in claim 9 wherein a gravity operated check valve is disposed in said receptacle outlet means.

11. In a water storage and dispensing system as set forth in claim 9 wherein said receptacle outlet means is provided with a valve seat and a gravity actuated check valve that is adapted to rest on said seat, said seat also being provided with valve by-pass grooves and the ratio of the cross-sectional area of the portion of said receptacle outlet means immediately adjacent said tube means to the cross-sectional area of the orifice of the tube means being on the order of 2:1, whereby water at relatively low rates and above 150° F. can be withdrawn from the receptacle and be mixed with the lower temperature water entering the receptacle inlet means prior to entrance of the water from receptacle into said dispensing conduit.
